(57) **CLAIM**

The ornamental design for a LED module, as shown and described.

DESCRIPTION

FIG. 1 is a front view of the LED module of the present invention.

FIG. 2 is a rear view of the LED module.

FIG. 3 is a top view of the LED module.

FIG. 4 is a bottom view of the LED module.

FIG. 5 is a left side view of the LED module.

FIG. 6 is a right side view of the LED module.

FIG. 7 is a first perspective view of the LED module; and,

FIG. 8 is a second perspective view of the LED module.
